UNITED STATES PATENT OFFICE.

CHATHAM E. BOWMAN, OF NEW YORK, N. Y., ASSIGNOR TO SAMSTAG & HILDER BROS., INC., OF NEW YORK, N. Y., A CORPORATION OF NEW YORK.

DESIGN FOR A CHILD'S APRON.

Application filed March 3, 1926. Serial No. 16,759. Term of patent 3½ years.

To all whom it may concern:

Be it known that I, CHATHAM E. BOWMAN, a citizen of the United States, residing at New York city, in the county of New York and State of New York, have invented a new, original, and ornamental Design for Child's Apron, of which the following is a specification, reference being had to the accompanying drawing, forming part thereof, in which the figure is a front view of the child's apron, showing my new design.

I claim—

The ornamental design for a child's apron as shown.

CHATHAM E. BOWMAN.
